UNITED STATES PATENT OFFICE.

JOHN W. DANIEL, OF OWENSBORO, KENTUCKY, ASSIGNOR OF ONE-HALF TO WILLIAM A. SUTHERLAND, OF OWENSBORO, KENTUCKY.

CHANGE-MAKING MACHINE.

1,231,858.

Specification of Letters Patent.

Patented July 3, 1917.

Application filed October 9, 1916. Serial No. 124,532.

To all whom it may concern:

Be it known that I, JOHN W. DANIEL, a citizen of the United States, residing at Owensboro, in the county of Daviess, State 5 of Kentucky, have invented a new and useful Change-Making Machine; and I do hereby declare the following to be a full, clear, and exact description of the invention, such as will enable others skilled in the art to 10 which it appertains to make and use the same.

This invention relates to the art of coin handling, and more particularly to a new and useful and practical change making machine, and one of the objects of the invention 15 is to provide a machine of this kind comprising novel features of construction.

Another object of the invention is to provide a machine of this kind having a plurality of magazines for holding the several denominations of coins, from pennies to silver dollars, inclusive.

A further object of the invention is to provide a plurality of slides for each magazine 25 whereby one or a multiple of coins may be discharged at one time, by one depression of a key.

A further object of the invention is to provide five slides for each magazine, there being 30 a key connected to each slide, and the slides being so constructed, that by depressing the key connected to the lowermost slide, a single coin may be discharged, and by pressing a second key of this series, the slide 35 immediately above the lowermost slide will be actuated and with it the lowermost slide, thereby discharging two coins. As depressing each of the other keys of this series an additional coin is discharged, until pressing 40 the last of this series, five coins at one time can be discharged.

Another object of the invention is to provide means for limiting the upward movement of the keys.

45 Another object of the invention is to provide means for limiting the backward movement of the slides, and to provide means for holding the slides one above the other.

A further object of the invention is to 50 construct each magazine in two sections hingedly united, whereby, upon removing the back of the machine, the sections of the magazine may be opened, so as to receive the coins.

55 A further object of the invention is to

provide means for holding the back of the machine in place detachably.

In practical fields, the details of construction may necessitate alterations, falling 60 within the scope of what is claimed.

The invention comprises further features and combination of parts, as hereinafter set forth, shown in the drawings, and claimed.

In the drawings:—

Figure 1 is a view in front elevation of 65 the improved change making machine, constructed in accordance with the invention.

Fig. 2 is a sectional plan view, showing parts in elevation of said machine.

Fig. 3 is a sectional view on line 3—3 of 70 Fig. 2.

Fig. 4 is a rear elevation of the machine.

Fig. 5 is a view partly in section and partly in elevation showing a portion of one of the magazines, and a multiple of slides 75 for discharging the coins from said magazine.

Fig. 6 is a view similar to Fig. 5 showing two of the slides as having been moved, showing two coins in the act of discharging. 80

Fig. 7 is a view similar to Fig. 5, but showing the multiple of slides partly in section, showing that the coins from the magazine fill all the registering openings of the five slides.

Fig. 8 is an enlarged detail perspective view of one bank of slides, showing a single key connected to one of the slides.

Fig. 9 is a detail perspective view of a portion of a comb for the keys, showing one key 90 mounted therein.

Fig. 10 illustrates collective views of one bank of slides, showing the slides separated.

Fig. 11 is a vertical sectional view through one of the magazines.

Fig. 12 is a sectional view on line 12—12 of Fig. 11.

Fig. 13 is a detail perspective view of portion of the back of the base frame 1, showing the stepped flanges to which the 100 springs of the slides are connected.

Referring more especially to the drawings, 1 designates the base structure or frame of the machine, which is mounted on the usual legs 2, which are provided with the usual 105 rubber buffer feet 3, and rising from this base frame is a substantially vertical extension frame 4. Cast or formed with the base frame 1 on the interior thereof is a supplemental frame 5 having a bed plate 6, to 110

support a plurality of banks of slides 7. The slides of each bank are provided with openings 8 which are circular in contour, and the diameters of which correspond to the diameters of the different coins from pennies to silver dollars, inclusive. Spaced from the auxiliary or supplemental frame 5 is a partition 9, between which and the portion 10, the coins from the slides may pass 10 into a suitable receptacle, not shown, below the frame 1, when the slides are actuated. A plate or bar or strip 11 extends transversely of the frame 1 and is spaced above the bed plate 6, so as to engage the uppermost slides of the several banks of slides, to hold them together. The slides of each bank are constructed alike, therefore, only one bank of slides is described, hence, corresponding reference characters are applied 15 to the slides of the several banks. Referring to Fig. 10 of the drawings, it is to be seen that the rear portion of each slide has a tongue 12, and it will be noticed that when the slides are placed one above the other, 20 the tongues 12 are out of registration, by reason of the fact that they project from different points of the rear edges of the slides. The lowermost slide is perfectly flat, but each of the upper successive slides has a 25 downwardly extending flange 13, so as to overlie the rear edge of the adjacent under-slide, so that when any one of the slides above the lowermost slide is pulled, the under slides are simultaneously pulled. The 30 flanges 13 are so arranged and of such length as to coöperate with the tongues of the slides between the uppermost and the undermost slides, so as to guide such slides, when actuated. Coiled springs 14 are 35 provided, one end of each of which is connected to one of the tongues 12. The rear wall of the base frame on its interior is provided with a plurality of flanges 15, which are arranged in banks, and the flanges of each 40 bank according to the banks of slides are arranged in stepped relation, and the rear ends of the springs 14 are connected to these flanges 15. The forward ends of the slides have apertures 16, and it is to be noted that 45 the lowermost slide of each bank is provided with a beveled edge 17 at its forward portion extending toward the left, the next slide of each bank is provided with opposite beveled edges 18 at its forward end. The 50 next two slides are likewise provided with opposite beveled edges 19, while the uppermost slide has a beveled edge 20 extending toward the right. In other words, the forward ends of the slides of each bank, are so 55 beveled that the forward extremities of the slides in front view are in stepped relation, so that the links 21 may be connected to the forward extremities of the slides by the pivot pins 22 which pass through the apertures 60 16. Extending transversely of the forward 65 16. Extending transversely of the forward

portion of the base frame 1 is a transverse plate 23 having vertical slots 24, thereby constituting what may be termed a comb, to guide the several keys 25 in their downward movements. This plate 23 is provided at 70 its ends with right angle extending flanges 26, in which the transverse pivot rod 27 is mounted. The keys 25 are pivotally mounted upon the rod 27 as shown in Fig. 3. The keys in side elevation are U-shaped, and are 75 arranged in banks, according to the denomination of the several coins from one cent to silver dollars, inclusive. The keys are provided with the usual buttons 28, on which the amounts of the several denominations 80 are shown, as shown in Fig. 2, clearly. The rear arms 29 of the keys are pivotally connected by the pins 30 to the links 21. Say, for instance, should anyone of the rearmost buttons of the keys be depressed, the lowermost slide of the respective bank of slides will be moved forwardly against the action of the spring 14. Should the next key of the same bank of keys, say, for instance, the dime keys, be depressed, the slide immediately above the lowermost slide of the respective bank of slides will be actuated, and with it, the lowermost slide. It is to be noted that the uppermost slide of each bank of slides, upon one of its longitudinal 90 edges is provided with an upstanding flange 31, the rear end of which engages the forward edge of the plate 11, thereby limiting the uppermost slide in its rearward movement, and owing to the downwardly extending flanges 13 of the other slide said other slides are limited in their rearward movements. However, the upper forward inclined wall 32 of the base frame 1 has 95 openings or slots 33 for the reception of the forward arms 34 of said keys. The rear edge of each slot 33 limits the upward movement of the respective key 25, by virtue of the arm 34 coming in contact with said edge, and which contact occurs about the same 100 time that the rear edge of the flange 31 engages the plate 11, therefore the slides and keys are limited in their initial positions simultaneously, thereby relieving the strain on each other. The ends of the comb or 105 plate 23 have extension flanges 35, which are secured to the bottom wall of the base frame by means of suitable screws or bolts 36, thereby anchoring the comb or plate in place. The upper ends of the slots 24 of 110 said comb or plate 23 also limit the keys in their upward pivotal movements. Extending transversely of the base frame is an elongated strip 37, the ends of which are secured to the cylindrical pieces 38, one of 115 which is mounted in the bearing 39 at one side of the base frame, while the other may be rotated and locked in a bearing barrel lock 40 at the opposite side of the base frame 1, by means of a suitable key 41. 120 125 130

When one of the cylindrical pieces 38 is locked, the strip 37 is in the position shown in full lines in Fig. 3, to engage the under-edges of the keys 25, thereby preventing the keys from being depressed. However, when the strip 37 is thrown down, as shown in dotted lines in Fig. 3, one of the cylindrical pieces 38 is unlocked, and while in this position, the keys may be actuated or depressed.

10 The vertical extension frame 4 is provided with a glass front 42, through which the several magazines for the coins are visible. These magazines 43 are tubular, and are of contours corresponding to the diameters of the several denominations of coins, from pennies to silver dollars, inclusive. Each magazine consists of two sections 44 and 45, as shown in Figs. 11 and 12. These sections are hingedly united by the hinge connections 46, there being a spring clasp or strip 47 secured at 48 to the section 45, so that the notch 49 of the spring clasp may engage the lug 50 of the section 44, to hold the section 45 closed. The front wall of the 25 section 44 of each magazine has a vertical slot 51, whereby the coins in the magazine are visible, and adjacent one edge of the slot 51 of each magazine, a scale 52 is applied, showing the number of coins in each magazine. This scale is in series of fives. On the front wall of the extension casing or frame 4 at its lower part there is provided notations of the denominations of the coins to be deposited in the magazines, that is from 30 pennies to silver dollars inclusive, as shown in Fig. 1. The upper wall of the extension casing or frame 4 has upon its under surface a series of rings 53, each angular in cross section, and secured by screws 54 to the 35 upper wall 55 of the extension casing. The respective magazines are secured in their respective rings 53, by means of suitable rivets 56. In fact, only the section 44 of each magazine is secured in one of said rings, therefore, the section 45 is free to swing open 40 on its hinged connection. The back 57 of the extension casing 4 is removable. Any suitable or conventional form of barrel lock 58 is carried by the back 57, and may be 45 locked and unlocked by means of a suitable key 59. A plate 60 is carried by a rotatable part, not shown, of said barrel lock, so that when the barrel lock is unlocked, the circular plate 60 may be rocked, by turning or rotating the knob 61. The plate 60 is provided 50 with radially extending diametrically opposite ears 62, to which the links 63 are pivoted. Secured on the inner face of the back 57 adjacent its upper and lower edges are 55 bearing straps 64, in which the lugs 65 of the bolt bars 66 are mounted and guided. The links 63 are in turn pivoted to the bolt bars, as shown in Fig. 4. When the back 57 is in position, as shown in Figs. 3 and 4, the 60 lugs 65 engage the inner faces of the upper

and lower flanges 67 and 68 of the extension casing 4, to hold the back locked in place. It is to be noted that when the circular plate 60 is rotated in the direction of the arrow *a*, the bolt bars will be moved toward each other, thereby withdrawing the lugs 65 from the path of the flanges 67 and 68, thereby permitting the back to be removed. When the back is removed, the sections 45 of the magazines may be swung open to permit the 70 coins to be placed or deposited in said magazines. Referring to Fig. 2, it is to be seen that the plate 11 is provided with a plurality of semi-circular scallops 69, corresponding to the diameters of the several 75 magazines. When the slides are drawn back by virtue of the springs 14 to their initial position, so the openings 8 of said slides will register with their respective magazines, the flanges 31 of the uppermost slides of the 80 several banks thereof will contact with those portions 70 (between the magazines) of the plate 11, thereby, as before stated, limiting the slides in their rearward movements. If change for five dollars is desired, 85 the second dollar key from the rearmost dollar key may be depressed, thereby discharging two silver dollars, then the rearmost three half dollar keys may be depressed, thereby discharging three half dollars, the total so far of the change being 90 three and a half dollars, then, the fourth quarter key from the rear may be depressed, thereby discharging four quarters. The total now is four and a half dollars. Then the second dime key from the rear may be depressed, then the fifth nickel key from the rear, and the fifth penny key from the rear depressed, thereby making a total of 95 five dollars in change consisting of two silver dollars, three half dollars, four quarters, two dimes, five nickels and five pennies. Upon a close examination or observation, it is clearly evident how changing of other bills may be made in other amounts of coins. 100

The invention having been set forth, what is claimed as new and useful, is:—

1. In a change making machine, a plurality of coin holding magazines arranged vertically in parallelism, a bank of superimposed slides having registering openings in registration with the lower end of each magazine, a transverse plate having a plurality of semi-circular recesses for the reception of the lower ends of the magazines, 115 said transverse plate having projections adjoining the recesses and extending between the magazines, means having linked connections with the forward ends of the slides of each bank for actuating the slides, the 120 uppermost slide on one edge having an upstanding flange to extend partly between the magazines, whereby its rear end edge may contact with the edges of said projections, 125 to limit the uppermost slide in its rearward 130

movement, the rear ends of the slide having overlapping flanges in stepped relations, whereby the lowermost slides are limited in their rearward movements, when the uppermost slide is limited, and spring means connected to the rear ends of the slides for returning the same.

2. In a change making machine, a casing having a transverse supporting frame and 10 provided with a partition spaced from the frame forming an opening extending entirely transversely of the casing, a transverse plate in the casing spaced above the frame and provided with semi-circular recesses, said plate having projections adjoining the recesses, a plurality of magazines arranged vertically and in parallelism and having their lower ends so engaging said recesses whereby said projections extend 15 partially between the magazines, a plurality of banks of coin discharging slides, the slides of each bank superimposed and arranged under the plate and having their forward ends supported by the partition, 20 and provided with coin receiving registering openings, the rear part of the slides of each bank being supported on the frame, whereby the openings of the slides will register with the magazine of each bank, and 25 so that said frame will half cover the openings to support the coins therein, spring means connected to the rear ends of the slides of each bank, means having linked connections with the forward ends of the 30 slides of each bank to actuate the slides against the action of the spring means, the uppermost slide of each bank having an upstanding flange extending partially between two adjacent magazines whereby its rear 35 end edge may contact with said projection to limit the uppermost slide in its rearward movement, the rear ends of the slides of each bank having overlapping parts in stepped relations to limit the lowermost slides in 40 their rearward movements when the uppermost slide is limited.

3. In a change making machine, a casing having a transverse plate provided on its forward edge with projections, a plurality of magazines arranged vertically in parallelism and having their lower ends arranged, whereby said projections extend partially between the magazine, a plurality of banks, 50 coin discharging slides disposed under the plate, the slides of each bank superimposed and provided with coin receiving openings

registering with one of the magazines, said casing having supporting means holding the banks of slides adjacent to and under the plate, and half covering the openings of the banks of slides, whereby the coins are supported in said openings, means carried by the uppermost slides of each bank to contact with said projection, thereby limiting the uppermost slides, the lowermost slides having superengaging means to limit the lowermost slides when the uppermost slides are limited, means connected to the forward ends of the slides for actuating the same, spring means arranged in stepped relations for each bank of slides, the rear ends of the slides of each bank having tongues arranged in stepped relations and to which said spring means is attached, whereby the spring means may pull direct on the slides for returning the same, and means arranged in stepped relation and carried by the rear of the casing for attaching the spring means in alinement with the slides of each bank.

4. In a change making machine, a casing, 80 a plurality of magazines arranged vertically in parallelism in said casing, a plurality of banks of slides having coin receiving registering openings, the slides of each bank superimposed whereby their openings register with one of the magazines, supporting means for the banks of slides, operating means for the slides of each bank and provided with connecting links, the forward ends of the slides of each bank having their 85 side edges cut away in stepped relations, whereby the connecting links of the operating means may be connected to the slides, the opposite side edges of the forward ends of the slides being cut away in reverse stepped 90 relations, whereby the connections of the links will not interfere with the free movements of the slides, spring means for returning the slides of each bank to their initial positions, means for limiting the uppermost slide of each bank, the lowermost slide of each bank having interengaging means to limit the lowermost slides when the uppermost slides are limited.

In testimony whereof I have signed my 105 name to this specification in the presence of two subscribing witnesses.

JOHN W. DANIEL.
